UNITED STATES PATENT OFFICE.

AMALIE VON CHIGOR, OF NEW YORK, N. Y.

FLAT-IRON HEATER AND HOLDER.

SPECIFICATION forming part of Letters Patent No. 663,117, dated December 4, 1900.

Application filed September 21, 1899. Serial No. 731,176. (No model.)

To all whom it may concern:

Be it known that I, AMALIE VON CHIGOR, a citizen of the United States, residing at New York city, county of New York, and State of New York, have invented certain new and useful Improvements in Flat-Iron Heaters and Holders; and I do hereby declare the following to be a full, clear, and exact description of the invention, such as will enable others skilled in the art to which it appertains to make and use the same.

The object of this invention is to heat flat-irons.

The invention consists in a recessed flat-iron, a table-bracket to support a flat-iron, a Bunsen gas-burner, a flat-iron having a hood or guard over the main body of the iron, a recess, and a supporting-plate.

Figure 1 is an elevation showing the bracket and how the flat-iron is held in place while being heated. Fig. 2 is a right-hand end view of Fig. 1 having the iron removed. Fig. 3 represents in elevation a side view of the flat-iron, hood, and draft-holes. Fig. 4 is a perspective and cross-sectional view of the hood on line α of Fig. 3. Fig. 5 is a right-hand end view of Fig. 3, showing the recess for admitting the bracket-burner or iron-supporter. Fig. 6 shows the skeleton frame of the iron with the guard removed. Fig. 7 represents in elevation a supporting-plate for heating any article, and Fig. 8 is an end view of the supporting-plate removed from the bracket-burner.

A in the several figures represents a flat-iron having a base A^2 , a heel A' , point A^3 , handle A^{12} , which is held in place by the brackets A^{10} , and screws A^{11} , as shown in Figs. 1, 3, and 5. The iron base A^2 is provided with a recess A^9 , as shown in Figs. 1 and 5, which is formed by the ribs A^5 , placed at intervals and cast integral with the base, as shown in Fig. 5.

B in the several figures is a guard or hood made to fit over the base, as shown in Figs. 3 and 5, and is held in place on the base by aid of the screws A^{11} , which pass through the guard and enter the screw posts or lugs A^8 , Fig. 6. This guard forms a protection, keeping the heat from reaching the hand of the user, and assists the draft of the flame of the burner through the medium of the holes B' ,

which are located near the base and at the top of the hood.

D in Figs. 1, 2, and 7 is a bracket provided with arms D^3 and D^4 , which form a space for the table leaf or board C. The bracket is held in place by aid of the thumb-screw D^9 and plate D^8 , which is supported in the bracket-lug D^7 . This bracket is provided with a Bunsen-burner tip D' , which supports the flat-iron while being heated, as shown in Fig. 1.

D^{28} is a passage through the bracket D for the gas and air necessary to feed the burner.

D^{10} is a loop having a recess D^{11} , as shown in Fig. 1, which forms a passage for air to mingle with the gas as it flows from the tip E' to the holes D^{14} of the Bunsen burner D.

E, Figs. 1 and 2, is a gas-post-tube burner having tip E' and stop-cock E^2 , which are supported by the loop D^{10} .

D^6 , Figs. 1 and 2, is a bracket having a trough D^{15} , in which curling or other irons may be held while being heated. It is provided with a loop D^5 , which prevents the iron from tipping down.

F, Figs. 7 and 8, is a shelf-bracket having rings F' , forming recesses F^8 , which are of sufficient size to fit on the burner D'. That the shelf may not turn upon the burner, a recess D^{16} is formed in the flange D^2 , which receives the finger F^2 , as shown in Fig. 7.

D^{12} , Fig. 1, is an arm extending out from the main bracket D and is provided with a hook D^{13} , Fig. 2, on its free end, which engages with the handle part A^{10} of the iron and prevents it from slipping off from the burner. This arm D^{12} holds the flat-iron upside down, which brings the base A^2 in line of the upward action of the heat of the flame and heats it more readily than in an upright position.

The operation is as follows: The bracket D is secured to any suitable table or board. A rubber gas-tube is then connected to any gas pipe or burner and then slipped onto the post E. The gas is then turned on and the burner D' lighted. The flat-iron A is then slipped onto the burner and swung around until the handle A^{10} rests against the arm D^{12} and in the rear of the hook D^{13} . After the iron is properly heated it is swung around and removed.

When the plate F is to be used, it is slipped onto the burner, as shown in Fig. 7.

I do not limit my invention to a removable

bracket-burner, as my burner may be secured to any gas-jet.

Having thus fully described my invention, what I claim as new, and desire to secure by

5 Letters Patent, is—

1. The bracket D, provided with the air-inlet D¹¹, the air-passage D²³ and a hook D¹³, a Bunsen-burner tube D' supported by said bracket, said tube having a series of holes D¹⁴ along its side, and the flat-iron A⁹ to receive the burner-tube and a handle A¹⁰ to contact with the hook D¹³, as and for the purpose specified.

2. The bracket D, having an air-inlet D¹¹ and a gas-outlet E' coöperating with said inlet and having a hook D¹³, in combination with the Bunsen-burner tube D' having a series of holes along its side, and a flat-iron constructed to surround the Bunsen-burner tube 20 and be heated thereby through the impingement of the Bunsen flame on the bottom of the flat-iron, as and for the purpose specified.

3. The bracket D, for supporting the Bunsen-burner tube D' and having recess D¹¹, passage D²³, and gas-outlet E', in combination with the Bunsen-burner tube D' for supporting and holding the flat-iron A, bottom side up and in a horizontal position and the ventilated flat-iron A, having recess A⁹ for receiving the Bunsen-burner tube D', as set forth.

4. The bracket D, for supporting the Bunsen-burner tube D' and having the recess D¹¹ for receiving the finger F², and the gas-passage D²³, leading into the Bunsen-burner tube D', in combination with the Bunsen-burner tube D' for heating and supporting the flat-iron A, bottom side up and in a horizontal position and the ventilated flat-iron A, having 40 the recess A⁹, as set forth.

5. The bracket D having an air-passage D¹¹, a gas-passage D²³, and a hook D¹³, in combi-

nation with the Bunsen-burner tube D' and a plate F to be supported by said tube and having a finger F² to enter the recess in the member D², as set forth.

6. The bracket D, having arms D⁸, D⁴ and the screw D⁹ coöperating with said arms, the bracket having also gas and air passages and carrying a hook D¹³, the Bunsen-burner tube D' mounted on the bracket D in combination with a flat-iron formed to receive the Bunsen-burner tube and to rest against the hook D¹³, as set forth.

7. The bracket D, having gas and air passages and carrying a hook D¹³ and the Bunsen-burner tube D' mounted on the said bracket, in combination with a flat-iron recessed to receive said Bunsen-burner tube when the iron is in an inverted position and having a handle to contact with the member D¹³, as set forth.

8. The bracket D, having passage D²³, recess D¹¹, finger D¹², and gas-outlet E', in combination with the Bunsen-burner tube D', and flat-iron A, having hood B, provided with holes B', and handle-support A¹⁰, as set forth.

9. The bracket D, having passage D²³, recess D¹¹, finger D¹², and gas-outlet E', for supporting the Bunsen burner D', in combination with the Bunsen burner D', and flat-iron A, having recess A⁹, stanchions A⁵, screw-lugs A⁸, and handle-support A¹⁰, to hold the flat-iron in a reversed position as set forth.

10. The bracket D, having passage D²³, recess D¹⁶, and Bunsen burner D', in combination with the plate F, having rings F', and finger F², as set forth.

In testimony whereof I affix my signature in the presence of two witnesses.

AMALIE VON CHIGOR.
